UNITED STATES PATENT OFFICE

ROSCOE G. PHELPS, OF CLEVELAND, OHIO, ASSIGNOR TO GENERAL ELECTRIC COMPANY,
A CORPORATION OF NEW YORK

METHOD AND APPARATUS FOR MAKING INCANDESCENT LAMPS AND SIMILAR
ARTICLES

Application filed May 7, 1927, Serial No. 189,514. Renewed April 26, 1929.

My invention relates to methods and apparatus for the production of electric incandescent lamps and other electrical devices comprising a filament, a bulb and a base, and, more particularly, devices in which the filament has a definite relation to the base. Heretofore it has been the practice in the manufacture of certain types of incandescent lamps to make an adjustment of position of the base with reference to the filament or of the filament with reference to the bulb, optical means being employed in the adjusting operation. One of the features of the preferred form of my invention is that such means are rendered unnecessary. A more important feature is that dependence is not made on a few adjustments but that the idea of definite relative positioning of the parts runs through the operations of mount making, sealing-in and basing. The object of my invention is to produce economically lamps and similar devices of uniform and attractive appearance and with their filaments very accurately positioned with reference to their bases. Other features and advantages of my invention will appear from the following description of a species thereof.

In the drawings, Fig. 1 is a perspective view illustrating an apparatus for the mounting of the filament on the stem; Fig. 2 is a perspective of a sealing-in machine; Fig. 3 is a plan view and Fig. 4 is an elevation partially in section of a neck moulding device comprised by said machine; Fig. 5 is a fragmentary perspective view of the driving mechanism for said machine; Fig. 6 is a perspective view of the lamp stem aligning jaws comprised by said machine and operating mechanism therefor; Fig. 7 is a fragmentary section through one of the sealing heads; Fig. 8 is an elevation of a portion of the basing machine; Fig. 9 is a plan view of a bulb-holding cup comprised by said machine; and Figs. 10 and 11 are elevations at right angles to each other of a lamp involving a modification of my invention.

In Fig. 1 is shown a mounting device which may be conveniently located adjacent to a

sealing-in machine for the purpose of accurately attaching and aligning filaments upon lamp stems prior to sealing the said stems into lamp bulbs. These lamp stems, as shown, are preferably of the tipless type such as disclosed in Mitchell and White Patent 1,423,956, and comprise a flare tube 10, an exhaust tube 11 and filament supporting and conducting wires 12-13 sealed in and extending from the flattened glass portion of the stem 14. This tipless stem assembly ready for the filament is placed upon a swivel arm 15 so constructed that the lower end of the flare tube 16 seats upon and the exhaust tube extends through a tubular member 17, which is substantially a duplicate of mount pins carried by the sealing-in machine, hereinafter described. In order to firmly support and align the stem upon the mounting device, I provide a clamp 18 which causes the exhaust tube to engage a groove in a block 18' aligned with the opening in mount pin 17. The insertion of the stem in the swivel arm 15 may be made at any convenient position of the latter, but, for the mounting of the filament, the arm 15 is caused to rest upon a stop 19. A slideable cutting block 20 is properly positioned on the base 21 to receive the projecting ends of the filament supporting wires 12-13 in shallow grooves 22 formed therein. After the positioning, a knife 23 is actuated to trim off ends projecting over the edge of the block 20, said knife being pivotally mounted at 24 and operated through a handle 25. The block 20 is then replaced by a pair of electrical conducting blocks 26-27 insulated from each other and partially grooved to receive the ends of the filament supporting wires. Mounted adjacent to the blocks 26-27 are a pair of electrical contact members 28-29 connected to a source of electrical energy. The terminal ends of a filament 30 are placed upon the ends of supporting wires 12-13 and the contact members brought into engagement with the contacting ends to fuse them together. The swivel arm 15 is then rotated to the vertical position against a stop 31 and by hand the filament is adjusted to the desired symmetry about the lower point of an aligning pin 32 which lies

in the principal axis through the tubular member 17. The amount thus completed is then transferred from the mounting device to a machine for sealing it into a bulb.

5 A form of sealing-in machine is shown in Figs. 2 to 7 inclusive and comprises a rotating table or turret 32 upon which are mounted a number of heads 33 each of which is arranged to hold a mount and bulb in proper relation to each other during the operation of sealing-in. The turret is carried by a central hollow shaft 34 which, as shown more particularly in Fig. 5, extends through a stationary table 35 of the machine, said table being in turn supported by a pedestal 36. By intermittently rotating the turret each of the heads is caused to stop for a definite time at each of various points or stations around the machine at which are located means having definite functions.

20 As shown in Fig. 5, the intermittent drive for the turret comprises a continuously rotating disc 37 mounted upon a counter shaft 38 driven from the main shaft 39 through a worm 40 and gear 41. Mounted upon the disc 37 is a grooved cam 42 which engages rollers 43, a number of such rollers being fastened to the underside of the turret. The shape of the cam 42 is such that when it engages one of the rollers 43, the turret is moved from one station to another.

25 In loading the machine a completed lamp mount is placed upon each of the heads 33 as they arrive at the loading position indicated as "A" in Fig. 2, a number of these heads being left out of the illustration for the purpose of clarity. These heads are non-rotatable and each comprises a means for supporting a bulb and a mount. The bulb supporting means comprises a partially closed ring 44 supported upon a pair of posts 45 extending from the turret 32, the inner surface of which has a plurality of protuberances 46 of suitable design upon which the bulb rests and which afford considerable stability thereto. The means for supporting the mount comprises a mount column such as shown in Fig. 7, wherein a collar 47 controlled by a yoke 48 and guided by pins 49 carries a hollow sleeve 50 within which is snugly fitted another hollow sleeve 51 the upper end of which supports a mount pin 52. The sleeve 51 has two portions of different internal diameter connected by a sloping shoulder 53 fitted with the head 54 of a slotted tubular pin 55 the body portion of which fits within the smaller diameter portion of the said sleeve. About the lower end of the pin 55 is placed a helical spring 56 in compression between the end of the sleeve 51 and a collar 57. In loading a mount upon one of the heads 33, its flare tube 10 is seated upon the mount pin 52 with the exhaust tube 11 extending into the slotted end of pin 55, the slot having been opened by 60 the raising of the pin by means of a shoe 59.

Prior to placing a bulb over the mount it is desirable to definitely locate and position the plane of the filament. This is accomplished mechanically by an aligning mechanism located at station B and shown more particularly in Figs. 2 and 6. As the turret pauses at station B, a suitably arranged pair of jaws 60-61 are caused to swing forward so as to close upon the sides of the flattened glass portion 14 of the stem, these sides being substantially parallel to and equidistant from a plane passed through the mid-point and terminals of the filament and the principal axis of the mount. The operation of the jaws is illustrated in Fig. 6 wherein a cam roller 62 at the end of lever 63 in passing from the high portion of a cam 64 permits a spring 65 to pull lever 66 to the stop 67, causing the bracket 68 to swing in toward the center of the machine carrying with it the aligning jaws 60-61. When the cam roller 69 at the end of lever 70 is acted upon by the high portion of the cam, the lever 71 is drawn away from its stop 72 and its fork end 73 acts upon a disc 74 so as to lift the yoke 75 against a compression spring 76 surrounding the rod 77. Upon the raising of the yoke a pair of links 78-79 carried thereby and attached at their opposite ends to the jaws 60-61 are forced outward causing the jaws to move toward each other so as to contact with the sides of the flattened glass portion of the stem 14. Further rotation of the cam 64 reverses the above described action so as to separate the jaws and move them away from the mount and out of the path of travel of the turret. While the jaws are closed the shoe 59 is removed from the lower end of the pin 55 and the helical spring 56 (Fig. 7) then forces the pin downwardly closing the slotted end of tube 55 on the exhaust tube 11 and rigidly supporting the mount.

70 The turret next moves to station C where an incandescent lamp bulb 80 is placed over the mount, said bulb being supported by the partially closed ring 44. The assembly comprising the mount and bulb is then carried through a number of stations where heat from a series of rotating burners 81 is applied to effect a fusion at the line of junction of the mount and bulb. As shown in Figs. 2 and 5, these fires are operated through a continuously rotating worm and gear drive 83 which imparts a uniform speed to the intermittent gear 84 to which is rigidly attached the rollers 85-86 and cam 87. The rollers are centered at the pitch radius of gear 84. To an adjacent whole gear 88 is rigidly attached a segment cam 89 carrying rollers 90-91, these rollers being centered at the pitch radius of gear 88. The gear 84 is sufficiently larger and contains sufficiently more teeth than gear 88, therefore the latter gear completes several revolutions while the gear 84 80 completes one revolution. Just as the gear 90

84 ceases imparting motion to gear 88 by reason of its blank portion 92 coming into contact with gear 88, the cam 87 picks up and continues the motion by driving against roller 91 while roller 86, by following the far edge of segment cam 89 steadies the motion. Cam 87 imparts a steadily decreasing motion to roller 91 and hence to the gear 88 until the motion approaches a pause. At this interval roller 85 is brought into contact with the near edge of segment cam 89, and roller 86 is about to cease following the far edge of segment cam 89, and roller 90 has been brought into contact with cam 87. Roller 85 now imparts increasing motion to segment cam 89 while roller 90 steadies the motion against cam 87. At the moment when roller 85 has reached the low point of the near edge of the segment cam, the gear 88 is being driven at a speed which is the same as that which will be imparted to it when it is in mesh with gear 84; so that at this point meshing of the teeth of the two gears 84 and 88 occurs, following which the gear 88 is driven a desired number of revolutions at desired uniformly highest speed before the interval of varying speed again is reached. Fig. 5 illustrates the conditions at a moment of approximate pause of rotation of gear 88. The motion imparted to gear 88 is transmitted through a suitable train of gears 93, 94 and 95 to gear 95' which is one of a series of similar gears intermeshing with each other so as to rotate the fire group to which each is attached.

At station D the surplus portion of the bulb neck is melted and blown off. It is requisite to direct air against the fused portion of the neck slightly below the line of union between the flare tube and the bulb. As shown in Fig. 7, in order to provide an air blast to blow off the bulb neck, a grooved passage 96 is provided along the exterior of the sleeve 51 which communicates with the atmosphere through a passage 97 formed in the outer sleeve 50. The mount pin 52 is provided with a flange 98 spaced from the top of the sleeve 50 so as to furnish the proper directing means for the air blast. The air is directed into the passage 96 through a pipe 99 carried by the collar 47. As the turret moves from station D toward station E the mount column is moved slightly downwardly by means of the collar 47 and yoke 48 to accomplish what is known as pulling down the lamp seal.

At station E heat from the rotating burners sufficient to soften the glass is applied to a portion of the bulb adjacent to the lamp seal. The turret is moved to station F. At this station a lever arm 100 actuated by the lower rim track of cam 101 causes a padded support 102 to rest, under tension of spring 103, upon the top of the bulb. And at the same time a spring tensioned lever arm 104 actuated by the upper and outer rim track 105 of

cam 101 and functioning through links 106 and levers 107, brings about the closure of a pair of mold segments 108 and 109 which meet below and out of contact with the softened glass of the lamp bulb (Fig. 4). The meeting of the mold segments causes the further action of the lever arm 104 to lift the closed mold segments vertically upwardly against the resistance of compression spring 110 exerted through a guided yoke member 111. This vertical lift of the mold segments is adjusted suitably in relation to the upper (mount seating) end of the mount pin 52 (Figs. 7 and 4). At the moment when the mold segments reach the top of their lift, air pressure from the pipe 112 introduced into the lamp through the pin 55, mount pin 52 and the exhaust tube 11 of the mount, is directed against the softened glass to expand it against the walls of the mold segments, and so to form a definitely shaped neck having a definite relation to the mount pin and hence to the lamp filament. The introduction of air pressure is signified by small arrows within the lamp bulb in Fig. 4. When the air pressure is relieved, the mold segments are lowered away from the lamp and are restored to their open position. These mold segments should be of such form as to shape the neck of the bulb to receive and position the lamp base. Where the lamp base is provided with pins or other parts which must have a definite position with reference to the filament, the form of segments illustrated in Fig. 3 may be used. These comprise the V-shaped notches 113—114 into which the softened glass is blown to produce a neck having the contour illustrated in Figs. 10 and 11 with protuberances adapted to engage slots in the base having a definite relation to said base pins. It may be desirable to alter the contour of the lamp bulb in a region more or less remote from the lamp seal. In such case, when the lamp is moved to positions such as G and H, heat is applied to said region which, as shown, is at the top of the bowl portion of the lamp bulb through the stationary burners 115—116 to soften the glass. Thereafter, as in position K, a mold member 117 is lowered, by means of a lever 118 and a step on the cam 101 and under tension of spring 119, to the lamp bulb. Air pressure is introduced to the lamp in the manner as previously described, which air pressure expands the softened glass against the walls of the mold member, producing a protuberance suitably shaped and arranged with relation to the mount pin 52 and hence with the lamp filament 30. The air pressure is then relieved and the mold raised from the lamp bulb.

One shape which may be produced by employment of mold member 117 is illustrated at 120, Fig. 2, a well-defined ridge contour symmetrically disposed in the principal axis of the mount column (heretofore described,

Fig. 7) and parallel to or symmetrically disposed in a plane passing through the mid-point and terminals of the lamp filament 30 and the principal axis of the mount column.

In Figs. 8 and 9 is shown a type of basing head forming part of a machine such as disclosed in Fagan and Malloy application, Serial No. 116,442, filed June 16, 1926, "Precision basing machine for incandescent lamps and similar articles." An incandescent lamp base 121 lined with cement is placed over the molded neck end of the accurately sealed lamp in proper relation for uniting, after which the bulb is placed in the spring tensioned holder 122 carried on the end of spindle 123. The bulb is conveniently supported and positioned with respect to its base because the protuberance 120 rests in the slot 124 formed in the holder 122. The spindle 123 is raised by the action of spring 125 until the pins 126-127 of the base 121 engage a plate 128 adapted to locate the pins in their proper plane with respect to that of the filament 30 and the protuberance 120 of the bulb. The plate 128 is provided with shoulders 129-130 located in a plane at right angles, for instance with the slot 124, and, as the base is raised the operator may adjust it so as to cause its pins to register with these shoulders. After adjustment a pair of jaws 131-132 are adapted to close so as to hold the base firmly while the assembly is carried through a heating means so as to harden the cement carried by the base and cause the said base to be securely attached to the lamp.

For the form of lamp bulb illustrated in Figs. 10 and 11 having protuberances 133-134 molded adjacent to the lamp seal and properly positioned with respect to the filament 30, it is necessary, merely to place a base 135 over the bulb neck with its slots 136 properly positioned with respect to its base pins, engaging the said protuberances.

45. What I claim as new and desire to secure by Letters Patent of the United States, is:

1. The combination of means for supporting an assembly comprising a bulb and stem having a depending exhaust tube, means for fusing a portion of said bulb, shaping means adapted to engage said fused portion, and means for delivering air through said exhaust tube to expand said fused portion against said shaping means.

55. 2. An apparatus of the class described comprising means for receiving and supporting a mount comprising a stem having a depending exhaust tube, means for supporting a bulb over said mount, means for fusing a portion of said bulb to said stem to form a seal, shaping means adapted to engage said fused portion, and means for delivering air through said exhaust tube to expand said fused portion against said shaping means.

65. 3. The method of accurately positioning

a filament of an electric incandescent lamp or similar device with reference to locating means carried by a base which includes locating in a sealing apparatus a mount comprising a glass stem and a filament with the latter definitely disposed relatively to the axis of the stem and with its plane having a definite relation to that of a flat portion of said stem and utilizing said flat portion to locate said stem definitely with relation to the head of said sealing machine.

4. The method of making an electric lamp comprising a light source definitely positioned with reference to a base locating member which comprises mounting said light source on a stem to form a mount with said light source occupying a definite position relatively to the axis of said stem, supporting a bulb over said mount so that it is axially aligned therewith, sealing said stem to said bulb, shaping the bulb to form a pair of projections having a definite relation to the plane of said light source and uniting a base thereto comprising means for engaging said projections and disposed definitely with respect to said base locating members.

5. An apparatus of the class described comprising a holder for receiving a stem, a pair of jaws and actuating means therefor adapted to cause said jaws to engage a flat portion of said stem and locate it in a fixed plane, a bulb support adapted to position said bulb over said stem in substantially axial alignment therewith, means for fusing portions of the neck of said bulb and said stem together, a mold comprising two sections adapted when closed together to shape the said fused bulb neck portion symmetrically with reference to the axis of said stem and means for closing said mold sections.

6. An apparatus of the class described comprising a holder for receiving a stem, a pair of jaws and actuating means therefor adapted to cause said jaws to engage a flat portion of said stem and locate it in a fixed plane, a bulb support adapted to position said bulb over said stem in substantially axial alignment therewith, means for fusing portions of the neck of said bulb and said stem together, a mold comprising two sections adapted when closed together to shape the said fused bulb neck portion symmetrically with reference to the axis of said stem and to form thereon a projection and means for closing said mold sections.

In witness whereof, I have hereunto set my hand this 4th day of May, 1927.

ROSCOE G. PHELPS.
